KNOB AND SPINDLE MECHANISM FOR DOOR LATCHES

Julius Miller, Brooklyn, N. Y.

Application July 7, 1938, Serial No. 217,862

1 Claim. (Cl. 70—149)

This invention relates to knob and spindle mechanism for door latches of the type in which a spring-projected latch bolt automatically engages a latch plate on a door jamb adjacent the edge of the door when the latter is closed, and which bolt is retractable within the door by means of a spindle or shaft that operates on the latch tumbler, thereby to release the bolt from the latch plate, the said spindle being operable by a knob at each end thereof.

The principal object of the invention is to provide means whereby one of the knobs is maintained permanently in operative engagement with the spindle while the other knob may be rendered alternately operative and inoperative by manipulation of the spindle, such manipulation being normally possible only at one side of the door.

A further object of the invention is to provide a door knob and plate combined as a unit whereby the knob cannot be removed from the spindle without removing the plate from the door, in combination with means for securing the plate to the door, which means is invisible at the outside of the door when the plate is in position thereon.

Other objects and advantages of the invention will appear as the description proceeds.

In the accompanying drawing, Fig. 1 is a longitudinal sectional view of a knob and spindle mechanism constructed in accordance with the present invention, attached to a portion of a door, both knobs being shown in operative engagement with the spindle;

Fig. 2 is a view similar to Fig. 1, but showing the spindle out of operative engagement with one of the knobs;

Fig. 3 is an end view of the knob shown at the left in Fig. 2, said knob being detached from its door plate; and

Fig. 4 is a perspective view of the spindle assembly with the permanently operative knob attached thereto.

Referring to the drawing, I designate a portion of a door which may be assumed to be hinged at one edge to the door frame and at its opposite edge provided with an automatically acting spring latch, the latch bolt of which (not shown) is actuated by a cam follower 2, through which passes a spindle 3 of generally square shape in cross-section, whereby rotary motion of the spindle will serve to rotate the cam 2 thereby to retract the latch against the tension of its spring. At one end of the spindle a knob 4 is secured thereto in the usual manner, namely, the corners

of the square spindle are threaded for engagement with an interiorly threaded bore in the shank of the knob 4 thereby to permit adjustment of the operative length of the spindle for use with doors of different thicknesses, the usual set screw 5 passing radially through the shank of the knob into engagement with one of the flat sides of the spindle for maintaining the knob in its adjusted position on the spindle. The shank of the knob 4 is provided at the end thereof adjacent the door with a cylindrical portion 4a of smaller diameter than the rest of the shank, said portion being adapted to pass freely through a central opening in a door plate 6. The said portion 4a has formed therein an annular groove 15 in which is mounted a split ring 7 preferably made of spring wire of round cross section.

At the opposite or outer side of the door, a plate 8 is provided in which is mounted for free rotation the shank of a knob 9, the end of the knob shank being flanged over at the inner side of the plate to prevent separation of the knob and plate, so that these two members constitute a unit. The plate 8 is preferably provided at its inner side with a plurality of interiorly threaded sleeves 10 seated in bores extending through the wood of the door, each of said sleeves being engaged by a screw 11 extending through the plate 6 at the other side of the door. This arrangement makes it impossible to remove the knob-carrying plate 8, or to locate the screws holding said plate, except from the inside.

The knob 9 is provided with an opening 12 therethrough, said opening being square for the greater portion of its length, while the spindle 3 is provided at the end thereof with a cylindrical portion 3a, immediately adjacent to the square portion.

Secured on the spindle, and disposed within an opening formed in the door, is a stop washer 14, which may either be threaded on to the spindle or merely provided with a square opening for the passage of the spindle therethrough, and in either case a set screw 15 passes radially through the washer and impinges on the spindle, thereby maintaining the washer at a fixed position. As will be noted in Figs. 1, 2 and 4, the washer is secured on the spindle at such a point as to leave only a short square portion 3b of the spindle at that side of the washer toward the knob 9, and the cavity in the door in which the washer is housed is wider than the thickness of the washer thereby to permit sufficient longitudinal movement of the spindle to carry the squared 55

portion 3^b into and out of engagement with the square opening 12 of the knob 9.

From the foregoing it will be obvious that the knob 4 is at all times secured to the spindle so that the latter will turn with the knob and thus impart rotary motion to the cam follower 2 thereby to retract the latch bolt whenever the knob 4 is turned. With the spindle in the position shown in Fig. 1, the knob 9 is also operative 10 to turn the spindle because the square portion 3^b of the latter is within the square opening 12 of the knob. However, assuming that the knob 9 is at the outer side of the door and it is desired to prevent operation of the latch bolt from that 15 side, this is accomplished by exerting a slight pull on the inside knob 4 to withdraw the square portion 3^b from its square seat in the knob 9, as shown in Fig. 2, in which position the knob 9 may be freely rotated around the cylindrical 20 portion 3^a of the spindle but is entirely ineffective to rotate the spindle. The longitudinal movements of the spindle in opposite directions are limited by the abutment of the washer 14 against the cam follower 2 on one side and against the 25 cam follower 2 on the other side and against the shank knob 9 and its plate 8 on the other side. The split ring 7 in its expanded condition is of slightly larger diameter than the opening in the plate 6 so that when the spindle is in engagement with knob 9 the ring abuts against the inner side 30 of plate 6 and offers sufficient resistance to the movement of the spindle to prevent accidental disengagement from said knob 9. On the other hand, owing to the cylindrical form of the stock from which the ring is made, a pull on the knob 35 4 causes the ring to contract sufficiently to enter the plate opening as shown in Fig. 2, the movement of the spindle being stopped by abutment of the washer 14 against the latch follower 2 before the ring passes completely out of the plate 40 opening.

It will thus be readily seen that, with the parts in the position shown in Fig. 1, the latch bolt may be operated by turning either knob, but in the position shown in Fig. 2, only the knob 4 is effective to rotate the spindle and thereby withdraw the latch bolt, and that the spindle can be replaced in operative engagement with knob 9 only by pushing on the knob 4 and, if necessary, turning the latter slightly to carry the square end 45 of the spindle into register with the opening 12 in the shank of knob 9. However, means is provided whereby a person who has accidentally 50

locked himself out by closing the door after him with the parts in the position shown in Fig. 2, may operate the spindle to withdraw the latch bolt. In the example shown in the drawing, the knob 9 is provided with a bore 15 in axial alignment with the square opening 12 and with the cylindrical portion 3^a of the spindle which is provided at its end with an interiorly threaded bore or socket 16 for engagement with the threaded end of a key 17, whereby one finding 10 himself locked out may thread the key into the socket and pull the spindle into operative engagement with knob 9, or by rotating the key until it will go no further without turning the spindle and thus withdrawing the latch bolt. While a 15 screw engagement between the spindle and key is shown herein, it will be readily seen that some other form of connection, such for instance as a slot and pin, may be devised to make it difficult for unauthorized persons to operate the spindle 20 from outside the door without having the implement designed for that purpose.

Having thus described my invention, what I claim is:

In a door latch having an automatically projected latch bolt and rockable means for retracting the same, an actuating spindle in slidable engagement with said retracting means and operative to actuate the same in all positions of the spindle, a knob secured to the spindle at one end thereof for manually rocking and sliding the spindle, a washer secured to said spindle for limiting the sliding movement of the spindle in opposite directions, a second knob mounted for free rotation in alignment with the opposite end 30 of the spindle and provided with an opening for the reception of a portion of the spindle, said opening and spindle portion being of cooperating form in cross-section whereby when the spindle is slid in one direction it will be operatively engaged by said knob and when slid in the opposite direction the knob will be free to rotate without effect on the spindle, a door plate having an opening in which a shank portion of said first knob is mounted for rotation and sliding movement, said shank portion having a circumferential groove therein, and a split ring of resilient material mounted in said groove and presenting flexible resistance to sliding movement of the shank portion of the knob in said door 35 40 45 50 plate.

JULIUS MILLER.
